[57] CLAIM

The ornamental design for a self contained tea cup, as shown and described.

DESCRIPTION

FIG. 1 is a perspective view of a self contained tea cup showing my new design;

FIG. 2 is a top plan view thereof;

FIG. 3 is a bottom plan view thereof;

FIG. 4 is a rear elevational view thereof;

FIG. 5 is a front elevational view thereof; and,

FIG. 6 is a side elevational view thereof;

The broken line showing in FIG. 4 is for illustrative purposes only and forms no part of the claimed design.
